DESIGN FOR A DRESS ENSEMBLE

Samuel Chapman, New York, N. Y.

Application July 29, 1937, Serial No. 70,713

Term of patent 3½ years

To all whom it may concern:

Be it known that I, Samuel Chapman, a citizen of the United States of America, residing in the city of New York, county of New York, and State of New York, have invented a new, original, and ornamental Design for a Dress Ensemble of which the following is a specification, reference being had to the accompanying drawing, forming part thereof.

Figure 1 is a front view of a dress ensemble showing my new design.

Figure 2 is a rear view thereof.

Figure 3 is a fragmentary front view of the upper portion of the dress without the jacket.

Figure 4 is a rear view of Figure 3.

The characteristic feature of my design resides in the fitted jacket member of the ensemble, which jacket consists of a Shirred elastic body section and a ruffled collar and peplum as shown.

I claim:

The ornamental design for a dress ensemble substantially as shown and described.

SAMUEL CHAPMAN.
